[57] **CLAIM**

The ornamental design for variable resistance strap for exercise apparatus, as shown and described.

DESCRIPTION

FIG. 1 is a perspective view of a variable resistance strap for exercise apparatus showing my new design;

FIG. 2 is a side elevational view thereof, the opposite side view thereof being the same;

FIG. 3 is a top plan view thereof, the bottom plan view thereof being the same;

FIG. 4 is an end elevational view thereof, the other end elevational view thereof being the same; and

FIG. 5 is a cross-sectional view thereof taken along lines 5—5 of FIG. 2.

FIG. 1

FIG. 5

FIG. 3

FIG. 4

FIG. 2
